JOSEPH PRICE, OF NEW YORK, N. Y., ASSIGNOR TO THE GRISCOM-RUSSELL COMPANY, OF NEW YORK, N. Y., A CORPORATION OF DELAWARE.

HEAT EXCHANGER.

Application filed June 3, 1924 Serial No. 717,464.

The present invention relates to heat exchange apparatus and has to do particularly with the transfer of heat between a gas and a liquid.

5 In my co-pending application, Serial No. 645,735, filed June 16, 1923, there is described a heat exchanger particularly adapted to accomplish transfer of heat between two fluid mediums one of which is a gas. For 10 the purpose of securing effective heat transfer, the apparatus is provided with extended heat transferring members along which the gas in its passage thru the apparatus is filmed for the purpose of effecting an intimate 15 contact between the entire volume of gas being treated and the heat transferring surfaces of the apparatus. This extended heat transferring surface is provided in the form of fins of heat conducting metal fitted 20 over the heat transferring tubes and assembled in closely adjacent relation on the tubes. The heating element of the apparatus comprises a plurality of tube elements each consisting of a pair of tubes interconnected 25 at one end and opening at their other ends into suitable distributing chambers which serve to properly direct the flow of fluid thru the tubes.

The present invention constitutes a development or modification over the apparatus disclosed in my above mentioned co-pending application and contemplates particularly an improved construction and arrangement of the tubular heating unit which simplifies 35 and reduces the cost of construction of the apparatus, and which at the same time provides a flexible system of distributing the liquid thru the tubes of the heating element so that any desired distribution of flow 40 may be obtained without resulting limitation of any particular dimension of the apparatus. The present structure contemplates the elimination of the usual complicated and expensive waterhead or distributing chambers ordinarily provided for controlling the 45 distribution of the working fluid to the respective tubes of the heating element.

The present invention involves the idea of interconnecting certain of the tubes of the heating unit in pairs or in groups in the same fashion as disclosed in the above mentioned co-pending application. With this construction, the tubular heating unit of the apparatus is divided into a plurality of individual fluid conveying elements, certain 55

of the tubes of which convey the working fluid in its initial direction thru the apparatus while the remaining tubes convey the fluid in the reverse direction on its return passage thru the apparatus. It is a principal feature of this invention to provide individual return connections at both ends of the tubes of the heating unit, and in this way regulate the distribution of the working fluid throughout the heat transferring unit. In providing individual return connections at both ends of the heat transferring unit instead of providing the usual distributing chambers or waterhead at one end of the apparatus, the individual connections which replace the usual waterhead construction at one end are arranged to constitute connections between the respective independent elements formed by the provision of the individual return connections at the 75 other end of the apparatus. Working fluid is admitted at one end of the apparatus and after traversing the length of the heating unit is returned in the reverse direction along the unit by reason of the individual 80 return connections provided at that end of the unit. Upon completing its return passage thru one of the fluid conveying elements the fluid enters the return connection provided at the initial end of that element 85 and, by reason of these connections, is directed into the initial pass of a second element. With this arrangement a plurality of the individual fluid conveying elements are connected in series arrangement, and at the 90 same time fluid may be admitted to a plurality of such elements in parallel, so that a series-parallel arrangement of connections is secured. The return connections at the ends of tubes preferably assume the form of 95 integral boxes or chambers each provided with a suitable member for engagement with the frame of the apparatus to thereby furnish the necessary support for the tubes of the unit.

To obtain a desirable flexibility of design, so that any desired distribution of fluid flow may be obtained without limiting any particular dimension of the apparatus, I provide for admission of the working fluid 105 at a plurality of different points in the heating unit. By this arrangement, the tubes of the heating element are divided into a plurality of independent sections, the tubular elements in each of these sections being 110

connected in series-parallel arrangement as above described, and the various sections of the heating unit receiving and handling working fluid independently. The admission and discharge of the working fluid to the heat transferring tubes is accomplished by means of manifolds extending along the apparatus and having connection with the proper tubes of the heating element.

10 The invention contemplates the use of the individual return connections or water boxes at each end of the tube elements for structures wherein the elements consist either of a pair of tubes or of a number of tubes 15 greater than 2. In case of tube elements comprising more than 2 tubes, the different passes of the element may contain either a like number of tubes and likewise the total number of tubes in an element may be 20 either even or odd. This arrangement is advantageous in certain instances from the standpoint of facility of construction and flexibility of design.

I have illustrated a preferred embodiment 25 of my invention in the accompanying drawings in which Figure 1 is a horizontal section taken longitudinally of a fin tube heat exchanger embodying my invention; Figure 2 is a vertical section taken longitudinally 30 of the apparatus; Figures 3 to 6 are detail views illustrating portions of the apparatus; Figure 7 is a transverse sectional view taken on line 7—7 of Figure 2 showing the arrangement of the return connections at the 35 end of the heating unit; Figure 8 is a transverse sectional view showing the arrangement of the fin tube elements in the apparatus and the manner of supporting and aligning these elements at points intermediate their ends; Figure 9 is a transverse sectional view taken on line 9—9 of Figure 1 showing the manner of supporting the 40 ends of the heating elements; Figure 10 is a partial longitudinal sectional view showing the 45 arrangement employed for admitting working fluid to the heat transferring element at two points; and Figures 11 to 13 are detail views of modified forms of heat transferring elements.

50 Referring to the drawings, particularly Figures 1 and 2, 1 indicates the frame work of the apparatus which houses the heat transferring unit. The heat transferring unit consists of a plurality of tubes 2 extending longitudinally of the apparatus and provided throughout their length with heat conducting fins 3 assembled in closely adjacent relation upon the tubes. The space surrounding the tubes 2 constitutes the gas passage thru the apparatus and the gas is filmed along the surfaces of the closely spaced fins 3 and is thus brought into repeated and intimate contact with the heat transferring surfaces.

65 The tubes 2 of the heating unit are prefer-

ably arranged in transverse rows in the heating unit and working fluid is admitted to the tubes thru the medium of an inlet manifold 4 extending transversely of the apparatus and communicating with the initial pass of a plurality of the fluid conveying tubes. After traversing the length of the apparatus the fluid enters the return connections or water boxes 5 provided at the opposite end of the apparatus and is thereupon directed on its return passage along the apparatus thru the other tubes which are in communication with those return connections 5. The entire group of tubes 2 constituting the heat transferring unit are 70 divided into individual fluid conveying elements by means of the return connections 5. In the apparatus shown in Figures 1 to 10 each of the fluid conveying elements consist of a pair of tubes, but it will be understood 75 that these elements may equally well consist of more than two tubes after the fashion shown in Figures 11 to 13.

At the end of the heat transferring element opposite the water boxes or return 80 connections 5 is a similar set of water boxes 6 serving to interconnect the other ends of certain of the tubes 2. The water boxes 6 are each connected to receive fluid issuing from the return pass of one fluid conveying 85 element and to pass this fluid into the initial pass of a second element. With this arrangement a number of the fluid conveying elements will be connected in series thru the 90 medium of the return connections 5 and 6 100 at the respective ends of the heating unit. After the working fluid has traversed a number of the fluid conveying elements in series, it issues into the manifold 7 and is thereupon discharged from the apparatus. For the purpose of presenting a staggered 105 arrangement to the flow of gas thru the apparatus the tube elements may be slanted as shown in Fig. 9, so that the tubes are in effect arranged in a plurality of staggered 110 rows having adjacent tube ends of each row interconnected by the water boxes 5 and 6. 115

The return connections 5 and 6 consist of integral boxes or chambers into which the tubes have been suitably secured. Each of the boxes is provided with a projection or prong 8 which fits into a hole in a supporting strip 9 carried by the frame of the apparatus. By this means the tubes of the heating unit are supported at their respective 120 ends and at the same time are properly positioned with respect to the other elements of the apparatus. For the purpose of aligning the respective tubes and supporting them at a point intermediate their ends a series of supporting blocks 10 are provided. As shown in Figure 5, these supporting blocks 10 consist of a pair of identical sections adapted to be clamped around the tubes 2 of one fluid conveying element. The 125 130

supporting block 10 is dimensioned externally to exactly those dimensions intended to be occupied by one fluid conveying element. Upon assembly in the apparatus the 5 supporting blocks 10 lie adjacent each other, as shown in Figure 8, and thus serve to automatically align each tube element and locate it properly in the apparatus with respect to all of the other elements. These features 10 of supporting the tube elements at their ends and at one or more points intermediate their ends are disclosed in my co-pending application, Serial No. 705,982, filed April 12, 1924, and it will be understood that the present 15 invention does not broadly claim these features. Similarly the tube element employing more than two tubes, as indicated in Figures 11 and 13, is disclosed in the co-pending application just mentioned and is 20 not in its broad aspects a part of the invention.

In Figure 10 I have shown an arrangement for admitting working fluid to the heating unit at more than one point. The 25 inlet manifold 4 serves to admit fluid to a plurality of heating tubes 2, and after this fluid traverses a number of the fluid conveying elements in series it is discharged into the outlet manifold 7' from whence it is 30 conducted away from the apparatus. A second inlet manifold 4' is provided for admission of working fluid and likewise admits fluid to a plurality of the tubes 2 in parallel arrangement. After traversing a 35 number of the tube elements connected in series arrangement the fluid admitted thru the inlet manifold 4' is discharged into the outlet manifold 7 and from thence it is conducted out of the apparatus. With this arrangement the entire body of tubes above the inlet manifold 4' constitutes a single unit or section, while the remaining tubes of the apparatus constitute an independent group or section. The two groups of tubes receive 40 and handle working fluid independently. Each group consists of a plurality of tubes connected in parallel and also consists of a number of these groups connected in series. By thus providing separate groups of tubes 45 in each of which the fluid conveying elements are connected in series-parallel arrangement, it is possible to adapt the apparatus to all conditions encountered in operation without experiencing any serious difficulty 50 in the way of limitation of certain dimensions of the apparatus. For instance, if it is desired to have a narrow apparatus, the heat transferring tubes may be divided into two or more groups as indicated in Figure 10 with the result that the gas traversing the apparatus will be brought into heat transferring relation with several fresh supplies of working fluid and thus adequate heat transfer may be effected. On the other 55 hand, if the design were limited to an ar-

rangement wherein the entire heating unit consists of a single group of tubes connected in series-parallel arrangement with but one portion of the tubes devoted to the admission of working fluid, the amount of fresh 70 working fluid which can be supplied depends directly upon the width of the gas passage for the reason that the number of tube elements which are connected in parallel is determined by the width of this passage. With this arrangement, additional 75 working fluid could be provided for only by increasing the width of the apparatus. This situation the arrangement of Figure 10 avoids. 80

While I have illustrated a preferred embodiment of my invention, certain changes may be made within the scope of the appended claims. It is the intent of the invention to provide an apparatus for transferring 85 heat to or from a gas which employs the idea of providing individual return connections or water boxes at each end of the heating unit to thereby eliminate the usual complicated and expensive cast water head construction which is commonly employed in apparatus of this class. It is also the intent of the invention to provide in a heat exchanger employing this type of structure a flexible arrangement for distribution of 90 fluid thru the heating unit with the advantage that a marked flexibility of design results. 95

I claim:

1. Heat exchange apparatus of the class 100 described, comprising a passage for the gas being treated, a heat transferring unit comprising a plurality of fluid conveying tubes extending into heat transferring relation with the gas traversing the apparatus, individual connections at one end of said tubes for dividing the entire body of tubes constituting said heating unit into a plurality of individual fluid conveying elements having two passes for conveying fluid respectively in an initial and a reverse direction, heat conducting fins spanning all of the tubes of each of said elements, means for admitting working fluid to the initial passes of certain of said elements in a parallel arrangement of flow, individual connections at the other ends of said tubes for interconnecting the reverse flow passes of said parallel-connected elements with the initial passes of other elements, whereby a plurality of 110 groups of said elements conveying fluid in parallel arrangement are connected in series, and means for admitting working fluid to said fluid conveying elements at a second portion of the heating unit, whereby a predetermined character of fluid distribution to the tubes of the heating unit is effected without the provision of a water head. 120

2. Heat exchange apparatus of the class 125 described comprising a passage for the gas 130

being treated, a plurality of fluid conveying tubes extending into heat exchanging relation with the gas traversing the apparatus, individual connections at one end of said tubes for dividing the entire body of tubes into a plurality of individual fluid conveying elements having two passes for conveying fluid respectively in an initial and a reverse direction, heat conducting fins spanning the tubes of the respective elements to thereby render each element a unitary structure, individual connections at the other ends of said tubes for interconnecting the reverse flow passes of said fluid conveying elements with the initial passes of other elements, lugs provided on said individual connections at the respective ends of the apparatus, removable strips having holes for receiving said lugs to thereby support the heat transferring tubes at both ends of the apparatus, and members associated with the respective tube elements intermediate the ends thereof of dimensions identical with the dimensions of the space to be occupied in the apparatus by each element, whereby said members provided on each of said elements lie adjacent corresponding members on adjacent elements and thereby serve to properly locate and support the respective elements.

3. Heat exchange apparatus of the class described comprising a passage for the gas being treated, a plurality of fluid conveying tubes extending into heat exchanging relation with the gas traversing the apparatus, individual connections at one end of said tubes for dividing the entire body of tubes into a plurality of individual fluid conveying elements having two passes for conveying fluid respectively in an initial and a reverse direction, individual connections at the other ends of said tubes for interconnecting the reverse flow passes of said fluid conveying elements with the initial passes of other elements, lugs provided on said individual connections at the respective ends of the apparatus, and removable strips having holes for receiving said lugs to thereby support the heat transferring tubes at both ends of the apparatus.

elements, lugs provided on said individual connections at the respective ends of the apparatus, removable strips having holes for receiving said lugs to thereby support the heat transferring tubes at both ends of the apparatus, and members associated with the respective tube elements intermediate the ends thereof of dimensions identical with the dimensions of the space to be occupied in the apparatus by each element, whereby said members provided on each of said elements lie adjacent corresponding members on adjacent elements and thereby serve to properly locate and support the respective elements.

4. Heat exchange apparatus of the class described comprising a passage for the gas being treated, a plurality of fluid conveying tubes extending into heat exchanging relation with the gas traversing the apparatus, individual connections at one end of said tubes for dividing the entire body of tubes into a plurality of individual fluid conveying elements having two passes for conveying fluid respectively in an initial and a reverse direction, individual connections at the other ends of said tubes for interconnecting the reverse flow passes of said fluid conveying elements with the initial passes of other elements, lugs provided on said individual connections at the respective ends of the apparatus, and removable strips having holes for receiving said lugs to thereby support the heat transferring tubes at both ends of the apparatus.

In testimony whereof I affix my signature.

JOSEPH PRICE.
